UNITED STATES PATENT OFFICE.

FRANZ KRATZ AND GOTTLÖB HONOLD, OF STUTTGART, GERMANY, ASSIGNORS TO THE FIRM OF ROBERT BOSCH, OF STUTTGART, GERMANY.

ELECTRIC SWITCH.

1,277,223.

Specification of Letters Patent. Patented Aug. 27, 1918.

Original application filed March 9, 1915, Serial No. 13,200. Divided and this application filed April 12, 1918. Serial No. 90,740.

To all whom it may concern:

Be it known that we, FRANZ KRATZ and GOTTLÖB HONOLD, both subjects of the Emperor of Germany, residing at Stuttgart, Germany, have invented certain new and useful Improvements in Electric Switches, of which the following is a full, clear, and exact description, such as will enable others skilled in the art to which it appertains to

make and use the same.

This application is a division of our application Serial No. 13,200 filed March 9, 1915, and it is directed to the arrangement of resistance material in a motor starting switch for internal combustion engines on automobiles, motor boats and other moving vehicles. This resistance material must have large carrying capacity, inasmuch as the motor current required to overcome the static friction and the resistance imposed by the compressed gas in the cylinders sometimes reaches 200 to 500 amperes, depending upon the size of the engine. The large amount of heat suddenly generated in the resistance material as a result of this large momentary current must be dissipated, and it has therefore been customary heretofore to arrange the resistance as a separate unit apart from the switch, so that it is freely exposed to the cooling effects of the atmosphere. This prior arrangement is of considerable disadvantage in automobiles and motor boats where room is quite limited and complexity is to be avoided, because the resistance coils or grids require considerable free space and the electrical connections from the switch are troublesome.

In accordance with the present invention, the resistance is combined with the switch and yet proper provision is made for the rapid dissipation of the heat and for the reliable support of the resistance at all times. We accomplish these results by laying flat strips of resistance material around the sides and bottom of the switch casing away from interference with the operating parts of the switch, the resistance material being held in place between insulating material by a metal cover secured to an inner casing by fastening means passing between the strips. The ends of the strip are brought to binding posts on the back of the switch casing through openings which furnish passages for air currents, so that the strip is suitably ventilated and

the terminals thereof located away from the operator.

In the accompanying drawings illustrating a preferred form of our invention,

Figure 1 is a sectional elevation through the switch in depressed position; Fig. 2 is a section on line 2—2 of Fig. 1; Fig. 3 is an enlarged section on line 3—3 of Fig. 1; Fig. 4 is a rear elevation of the switch, partly broken away; Fig. 5 is an elevation of one side of the switch with the outer casing removed; Fig. 6 is an elevation of the other side of the switch, with some of the parts partly broken away; and Fig. 7 is a section through the casing particularly showing the arrangement of the resistance strip therein.

The hollow switch shaft *b* is longitudinally movable in a bearing *a'* of the switch-housing *a*, and it carries a head member *c* having a hinged cap *d*. The lock-bar *e* is fitted into the interior of the switch shaft *b* and is provided at the upper end with a key-hole *f* and at the other end with the projecting tongues *g* adapted to slide in the slots *h* of the upstanding guide-post *i*. These slots terminate in horizontal locking slots *h'* into which the tongues *g* may be turned to lock the switch shaft against depression from its raised position, the lock-bar *e* being longitudinally movable with the switch shaft and rotatable therein. The spring *k* tends to hold the switch shaft *b* in its raised position.

The switch shaft *b* carries the conducting switch bridge *l* and also an arm *l'* which cooperates with the conducting switch bridge *l''*. The contact studs *m* are mounted on the insulating material *w* and are electrically connected to the binding-posts *m'*. The switch bridge *l''* is adapted to maintain a set position, throughout a portion of the stroke of the switch shaft *b*, and to move therewith when the arm *l'* engages the upper or lower rim of the sleeve *l''* which is fast with the switch bridge *l''* and slidable on the post *i'*. The switch bridges *l* and *l''* are each composed of bent laminations of thin metal riveted together at *l''* and held between two clamping plates with flanges *p*. The insulation *l''* insulates the switch shaft *b* and the posts *i* and *i'* from the switch bridges *l* and *l''*. The nut *o* screwed on the end of the switch shaft forces the switch bridge against the member *o'*.

A continuous strip *r* of nickelin or other

suitable resistance metal, is laid around the sides and bottom of the switch-housing α . The folded strip is insulated on both surfaces by mica plates s and the outside is 5 covered by a metal sheet u fastened to the switch-housing α by rivets u' extending between the strips. The two ends of the strip r are brought through openings x in the back α of the switch casing, and are connected to the binding-posts v and m' .

10 Inasmuch as the resistance material r is called upon to carry the entire motor starting current, which, in some cases, may reach 200 to 500 amperes, the heat generated is 15 considerable, and must be dissipated in order to prevent warping of the strip and possible short-circuit thereof, and also so as not to overheat the operating parts of the switch. We have found that the openings x 20 in the back of the switch casing provide sufficiently well for the passage of air around the strip r in the casing and thereby prevent a hazardous temperature rise in the strip. Furthermore the rivets u' hold the folds of 25 the strip rigidly in place, and thereby resist the tendency of the strip to warp when heated.

Having thus described our invention, what we claim is:

30 1. In an electric motor starting system for engines, the combination with a starting switch, of a housing therefor providing a channel insulated on opposite walls, a strip

resistance in said channel, and fastening means drawing the opposite insulated walls 35 into firm contact with the strip resistance to hold it in place upon temperature changes therein.

2. In an electric motor starting system for engines, the combination with a starting 40 switch, of a housing therefor providing a channel with an opening to the atmosphere, and a strip resistance arranged in the channel and passing loosely through said opening, whereby the strip resistance is ventilated to dissipate the heat generated therein. 45

3. In an electric motor starting system for engines, the combination with a starting switch, a housing therefor providing a channel insulated on opposite walls and having 50 an opening to the atmosphere, a strip resistance arranged in the channel and passing loosely through said opening, and fastening means passing between the folds of the strip resistance and drawing the opposite insulated walls into firm contact with the strip resistance, whereby the strip resistance is held firmly in place in the channel upon temperature changes therein, and the heat generated is dissipated by air passing 55 into the channel from the atmosphere. 60

In witness whereof, we affix our signatures.

FRANZ KRATZ.
GOTTLOB HONOLD.
